TIMER

Henry E. Warren, Ashland, Mass., assignor to
 Warren Telechron Company, Ashland, Mass.,
 a corporation of Maine

Application August 4, 1939, Serial No. 288,360

5 Claims. (Cl. 200—39)

My invention relates to timers and particularly a timer for operating a switch or the like at a predetermined adjustable time interval following an operation which sets the timer into timing operation. It is the object of my invention to provide a reliable low cost timer of this type which is adapted for general application.

The features of my invention which are believed to be novel and patentable will be pointed out in the claims appended hereto. For a better understanding of my invention reference is made in the following description to the accompanying drawing in which Fig. 1 is a perspective front view of a preferred embodiment of my invention, and Fig. 2 is a partially sectional side of the central part of the apparatus as seen from the right of Fig. 1.

Referring to Fig. 1, 21 represents a timer motor. This motor may be a synchronous electric motor which operates continuously when the device is being used. Motor 21 drives the gear 32 which is part of a friction clutch. The other parts of the clutch consists of a spring 3 secured to a shaft 4 on which gear 32 is rotatable. Shaft 4 extends forward through a front plate 17, and has secured to it, at the rear of the plate, a latch member 7 and, to the front of the plate, a holding finger 5 co-operating with a stop 6. Motor 21 tends to drive shaft 4 in a counter-clockwise direction but when the holding finger 5 rests against stop 6 shaft 4 is held from rotation and the clutch 32—3 slips. A timing operation is initiated by removing stop 6 from holding position in any suitable way. In the illustration, stop 6 extends through a slot 33 in the front plate 17 and is pivoted at 34 to the rear of the plate. Stop 6 is normally held up against the upper end of slot 33 by a spring 24 and when in this position extends into the path of rotation of finger 5 and prevents rotation of shaft 4 and the attached finger 5 past this point. Finger 5 may be released by simply depressing stop 6 momentarily either manually or otherwise.

Rotatively mounted on shaft 4 to the rear of latch 7 is a disk 9. This disk is urged to rotate in a clockwise direction by a spring 11 which is always under more or less tension. Spring 11 may be coiled about shaft 4 between a pin 10 in disk 9 and an abutment 25. Disk 9 has a switch operating member 12 projecting radially from its forward face, which member serves to move a resilient spring blade 13 of a switch. One stationary contact of this switch is represented by screw 16 which is adjustably threaded through a suitable terminal block. Switch blade

13 is biased to engage with contact 16. An abutment 22 serves to limit the opening movement of switch blade 13 with respect to contact 16 and the rotation of member 12 and disk 9 in a clockwise direction. The abutment 22 may also serve as another stationary contact of the switch. The minimum tension of spring 11 is sufficient to definitely move and hold the resilient switch blade 13 away from contact 16 against abutment 22.

Pivoted to a post 23 extending from the front face of disk 9 is a latch arm 8 notched on its lower edge to co-operate with the latch member 7 on shaft 4. The free end of latch arm 8 extends to the left and may be lifted from engagement with latch member 7 by a pin 14 which pin extends from the rear of an adjustable dial plate 15. Dial plate 15 is rotatable about the same axis as shaft 4 and may have gear teeth in its periphery so as to be rotated by a gear 18 on a shaft 35. Shaft 35 extends forward through the front plate where it is provided with a thumb piece 36 for convenience in adjusting the dial 15 and hence the position of releasing pin 14.

The front plate 17 has an opening at 37 through which a portion of the graduations on dial 15 may be seen and a setting index 20 is provided on the front plate adjacent the opening for the purpose of setting any desired time graduation on disk 15 opposite thereto. Friction serves to hold said gear and dial 15 to the position to which they have been adjusted.

The operation of this device will be apparent from the following. The parts are shown in the idle position with finger 5 against stop 6 holding shaft 4 and catch 7 stationary. This may be referred to as the zero position of shaft 4. Spring 11 is under sufficient tension to hold disk 9 with its switch operating finger 12 in the initial position shown holding resilient switch contact 13 against abutment 22. In such positions of shaft 4 and disk 9, the notch on the lower edge of latch arm 8 is in engagement with the stepped surface of catch 7 secured on shaft 4 such that as soon as shaft 4 starts to turn in a counter-clockwise direction, disk 9 will also be rotated counter-clockwise through the driving connection of the latch parts 7 and 8 and immediately allow switch contact 13 to close on contact 16. If the device were adjusted for a zero timing interval, pin 14 on dial 15 would be against the lower edge of catch arm 8 and partially raising it so that it would release catch 7 by a slight counter-clockwise rotation of shaft 4. In such a case the switch contacts 13—16 would remain 55

open upon rotation of shaft 4. For such zero time interval adjustment the zero graduation of dial 15 should be opposite reference mark 20.

To set the device for a definite time interval 5 of operation, dial 15 is rotated counter-clockwise so as to move pin 14 away from the lower edge of catch arm 8 as indicated in Fig. 1. The time for which such adjustment is made will now be indicated opposite reference mark 20. 10 Thus in the illustration the device is adjusted for a time period of "2" time units. These time units may be minutes, seconds, fractions of a second, etc., depending upon how fast the motor 21 is arranged to drive shaft 4. For purposes of 15 illustration, let it be assumed that the time units marked on dial 15 represent seconds. Hence the device is now adjusted for a timing interval of "2" seconds. Motor 21 is assumed to be in operation and hence the friction clutch at 3 slips 20 because shaft 4 is held from rotation by stop 6. A timing interval operation is now started by simply momentarily depressing stop 6, thereby 25 starting to rotate in a counter-clockwise direction at a constant speed. Latch member 7 which is secured to shaft 4 also rotates and carries with it latch arm 8 and disk 9. Switch operating finger 12 moves away from contact 13 and it closes against contact 16. A very slight rotation 30 of shaft 4 is of course required before the switch will close but this is a constant amount for all settings and is taken into consideration in the graduation of the zero of dial 15. The torque on shaft 4 necessary to drive shaft 4 against the 35 tension of spring 11 is not sufficient to slip clutch 3, 32. Hence the switch is closed and disk 9 rotates counter-clockwise with shaft 4. In two seconds, in the example given, catch lever 8 is rotated against pin 14 and is raised to release it 40 from catch member 7. Counter-clockwise rotation of disk 9 also further tensions spring 11. Spring 11 then returns disk 9 and with it pin 12 to the initial position shown to open the switch 45 13-16. Shaft 4 and the parts 5 and 7 carried thereby continue to rotate until they have completed one revolution when stopped by stop 6, and the device is now ready for another timing 50 operation. If a different switching period is desired, the dial 15 is readjusted to a new position by turning thumb piece 36 until the desired time period appears opposite indicator 20.

As shown in Fig. 2 the latch arm 8 and rear end of pin 14 move in a plane, parallel to disk 9, which is to the front of the switch structure and 55 hence these parts are not interfered with by the switch structure and can rotate past the same. Switch operating finger 12 can rotate nearly 360 degrees until it comes against the rear of abutment 22. Thus nearly the entire 360 degree periphery of dial 15 is available for time setting 60 purposes. The holding surfaces of catch 7 and latch arm 8 are cut at such an angle that there is no binding or locking action which would prevent their release when arm 8 is being released 65 by its movement against releasing pin 14 and the pressure against pin 14 is not sufficient to rotate dial 15 nor is the added torque required sufficient to slip the clutch at 3.

Preferably the pin 10 to which the spring 11 70 is attached or another pin extends to the front of disk 9 outside of catch arm 8 to prevent arm 8 from swinging too far out and getting out of place when the time adjustments are such that this arm is released when arm 8 is beneath 75 shaft 4.

It will be noted that the zero time setting position is at a point where the latch parts 1 and 8 are above the shaft 4 and hence arm 8 is biased by gravity to the latching-in position. When these parts are beneath the shaft such that gravity tends to release arm 8, the driving force through this latch is sufficient to prevent release except as intended when arm 8 comes against releasing pin 15.

The contacts 13 and 16 may be included in 10 any control circuit to provide a predetermined adjustable time closure of the circuit. Likewise contact 13 and abutment 22 used as a contact may be included in another circuit to provide a predetermined adjustable time opening of the 15 circuit. Or, the switch may be used as a time controlled single pole, double throw switch. In case a continuous on and off time cycle is desired, the stop 6 may be withdrawn continuously by simply unhooking spring 24.

When the switch operating pin 12 returns to the switch operating position at the end of a timing operation it does so with some force due to the tension of spring 11. In order to prevent bouncing of pin 12 and chattering action of the contacts at this time I prefer to provide a fly wheel or inertia element 38 on disk 9 as best shown in Fig. 2. The inertia element 38 may be simply a disk in frictional engagement with disk 9, the two being urged together by a spring 39. When the disk 9 is returned to a zero position at the end of a timing operation and is suddenly stopped by pin 12 coming against its stop, inertia part 38 continues to rotate by a slight amount and the friction force between it and disk 9 is in a direction to oppose any reverse bouncing rotation of disk 9 at this time. This frictional force is made sufficient to prevent any bouncing action when the disk 9 returns to a zero position.

The gears shown between motor 21 and the 40 gear 32 are merely representative. Any desired gear ratio may be used and such gears may readily be changed to obtain a different timing rate of shaft 4. For remote or automatic starting of a timing operation, the stop 6 may be 45 withdrawn by a solenoid 40 (see Fig. 2). The presence of such solenoid does not interfere with manual operation of stop 6.

What I claim as new and desire to secure by 50 Letters Patent of the United States is:

1. A timer comprising a timer motor, a shaft, a slip friction clutch through which said shaft may be driven in one direction by said motor, a switch-operating member rotatively mounted on 55 said shaft, a spring urging said operating member to rotate in a direction opposite to the direction of rotation of said shaft, a stop for limiting such rotation of the switch-operating member, latch means having co-operating parts secured to said shaft and switch-operating member which, when engaged and the shaft is rotating, causes rotation of said switch-operating member with said shaft, means for releasing said catch parts after said switch-operating member has been rotated a predetermined adjustable part of a rotation from its 60 stop, and a switch operated by said switch-operating member when it is rotated away from and returns to its stop.

2. A timer comprising a timer motor, a shaft, 70 a slip friction clutch through which said shaft may be driven in one direction by said motor, a switch-operating member rotatively mounted on said shaft, a spring for urging said switch-operating member to rotate in a direction opposite 75

- to the direction of rotation of said shaft, a stop for limiting such rotation of the switch-operating member, latch means having co-operating parts on said shaft and switch-operating member which, when engaged in driving relation and the shaft is rotating, causes rotation of the switch-operating member away from its stop against the tension of said spring, removable stop means for stopping the rotation of said shaft in a position where the latch part thereon will engage in driving relation with the latch part on the switch-operating member when the latter is in its stop limiting rotary position, means for releasing said latch parts, said means being adjustable so as to release said latch parts at different desired rotary positions of the switch-operating member, and a switch operated by said switch-operating member when it moves away from and returns to its stop.
3. A timer comprising a constant speed electric motor, a shaft, a slip friction clutch through which said shaft may be driven by said motor in one direction, a switch-operating member mounted for rotation about said shaft, a spring for urging said operating member to rotate in a direction opposite to that in which the shaft is driven by said motor, a stop for limiting such rotation of the operating member, a removable stop for stopping rotation of said shaft in one rotary position, means having cooperating parts on said shaft and operating member for establishing a driving connection between said shaft and operating member when both are in their stopping positions, time graduated adjustable means for interrupting said driving connection after the operating member has been driven a predetermined adjustable part of a revolution away from its stop by said shaft, a switch operated by the switch operating member as it moves away from and returns against its stop, and an inertia fly wheel frictionally coupled with said rotary switch-operating member for preventing rebound of the latter when it is returned against its stop by said spring.
4. A timer comprising a rotary switch actuating member, a stop therefor, a spring biasing said actuating member to an initial rotary position against said stop, a switch biased to one position but held in another position by said actuating member when the latter is in its initial position, a shaft on the axis of rotation of the switch actu-
- ating member, means for driving said shaft at constant speed, means establishing a driving connection between said shaft and the switch actuating member when said parts are in one rotary position with respect to each other, such that the switch actuating member is driven away from its stop, said spring is tensioned and said switch is allowed to move to the position to which it is biased, means for interrupting said driving connection to permit the return of said switch actuating member to its initial position, said interrupting means being adjustable to vary the distance less than a complete revolution traveled by the actuating member from its initial position when such interruption occurs, and means for starting and stopping said shaft when it is at such rotary position as to establish driving connection with said actuating member when the latter is in its initial rotary position.
5. A timer comprising a drive shaft, a switch actuating member and a time graduated setting dial mounted for independent rotation on the same axis, a timer motor, a slip friction clutch through which said shaft is driven by said motor in a given direction, stop means for stopping the rotation of said shaft when it arrives at a zero rotary position, said stop means being removable from stopping position at will, a spring tensioned to rotate said switch actuating member in the opposite direction, a switch having a resilient movable contact member biasing the switch to closed position but held in an open position by said switch actuating member when in an initial position to which it will normally be rotated by said spring, a latch having co-operating parts on said shaft and switch actuating member through which the latter may be driven by said shaft against the tension of said spring to allow said switch to close, means on said time graduated dial for releasing said latch to allow the switch actuating member to return to its initial position, said dial being adjustable to cause such release at different rotary positions of said switch actuating member with respect to its initial position, said dial indicating the time the switch is closed during a timing operation, said latch parts being positioned to engage when said shaft is in its zero position and said switch actuating member is in its initial position.

HENRY E. WARREN.
